UNITED STATES PATENT OFFICE

FRED M. KERN, OF DETROIT, MICHIGAN, ASSIGNOR, BY MESNE ASSIGNMENTS, TO CINCINNATI GRINDERS INCORPORATED, OF CINCINNATI, OHIO, A CORPORATION OF OHIO

CENTERLESS GRINDING MACHINE

Application filed April 1, 1926, Serial No. 38,954. Renewed April 5, 1929.

This invention relates to centerless grinding machines and more particularly to centerless grinding machines in which the work is rotated and ground between a rapidly rotated grinding wheel and a slowly rotated work regulating wheel.

Heretofore, centerless grinding machines have been provided in which a work piece has been positioned for respective grinding and rotation between a rapidly rotated grinding wheel and a slowly rotated work regulating wheel having its axis skewed at a slight angle to the axis of the grinding wheel (where both wheels are of the peripheral type) so as to propel the work axially past and between the wheels. Such a machine is not adapted for grinding cylindrical work of special form, such as work having a shoulder or enlargement thereon, since the latter prevents complete passage of the work axially past the wheels.

It is an object of the invention, therefore, to provide a centerless grinding machine for grinding such special shapes of cylindrical work economically and accurately upon a commercial production basis.

It is a further object to provide a pipe or the like in a centerless grinding machine for supplying grinding fluid upon the work piece during the grinding operation which is constructed and arranged to convey the grinding fluid in the most advantageous manner upon the work regardless of any changes in the adjustments of the machine required on account of wear of the grinding wheel or so that work of different sizes may be ground.

The invention accordingly consists in the features of construction, combinations of elements, and arrangements of parts as will be exemplified in the structure to be hereinafter described and the scope of the application of which will be indicated in the following claims.

In the accompanying drawings in which is shown one of various possible embodiments of my invention,

Fig. 1 is a side elevational view, with parts broken away, of a centerless grinding machine embodying the invention;

Fig. 2 is a plan view of a portion of the

machine as viewed from above in Fig. 1 the grinding wheel and certain other parts being removed in order to show certain features of the construction more clearly;

Fig. 3 is a detail view of the rack for carrying the mounting for the work positioning member;

Fig. 4 is a detail view of the mounting for the positioning member;

Fig. 5 is a side elevational view of a portion of the machine of Fig. 1 and shows certain parts in section as seen along the line 5—5 of Fig. 2;

Fig. 6 is an elevational view, partly in section of the eccentric shaft which supports the mounting for the work positioning member; and

Fig. 7 is a diagrammatic view of a machine in which the wheels are disposed in substantially the same horizontal plane and which embodies certain features of the invention.

Similar reference characters refer to similar parts throughout the several views of the drawings.

Referring now to the drawings I have shown in Figs. 1 to 6 a machine embodying a preferred form of the invention comprising a frame 10 (Fig. 1) having a spindle 11 mounted at an upper portion thereof for rotation. A grinding wheel 12 is mounted on the spindle and is rotated rapidly and hence at a suitable grinding speed from any suitable source of power by means of a belt 13 passing over a pulley 14 secured upon the spindle 11. A column 15 is mounted for vertical movement in a lower front but preferably hollow cylindrical portion of the frame and is prevented from turning therein by a key 17 engaging a groove 18 in the column. A spindle 19 carrying a regulating wheel 20 is mounted for rotation in suitable bearings (not shown) within the bearing casting 21 upon the support 22 integral with or suitably secured upon the top of the column 15, and may be rotated relatively slowly from any suitable source of power, such as a motor 23 connected directly with a shaft 24 carrying a worm 25 which engages a worm wheel 26 secured upon the spindle 19. The two wheels are rotated in the directions indicated

100

by the arrows in Fig. 1 and it will be noted that the adjacent operative surfaces of the two wheels are thus made to travel in opposite directions relative to a point therebetween; the regulating wheel serves to control the rotation of work pieces of round section interposed between the two wheels, the grinding wheel performing a grinding operation thereon during such rotation.

An upwardly projecting bracket 27, formed preferably as an integral part of the column 15, is provided with vertically extending slideways 28 for receiving a slide 29 which may be adjusted vertically by turning a shaft 30 (see also Fig. 5) mounted in the bracket 27 and carrying a pinion 31 engaging a rack 32 on the slide 29. A water pan 33 is secured to the column 15 by means of bolts 34 passing from the column into the support 22. The regulating wheel 20 and the bracket 27, as well as the water pan 33, may be moved vertically by turning a screw shaft 35, which is mounted (see Fig. 1) so as to prevent longitudinal movement in a bearing (not shown) in the column 15 and is arranged to engage a threaded hole 36 in a boss 37 secured to or integral with the frame 10. The screw shaft 35 may be turned by means of a hand wheel (not shown) secured upon a shaft 38 carrying a worm 39 which engages a worm wheel 40 mounted upon the screw shaft 35.

In order that the work may be held in operative contact with the grinding wheel 12 and work regulating wheel while being ground to a predetermined size by the former and rotated by the latter, I provide a work positioning or movable work holding member adapted to move the work into the grinding throat between the wheels and preferably in a direction opposed to that in which the thrust of the grinding wheel is exerted thereon. Thus, referring to Fig. 1, the operative surface of the grinding wheel 12, adjacent the regulating wheel 20, will be seen to move in a direction from the left to the right, and I achieve many advantages by causing the work positioning member to move the work piece into operative relation to the two wheels in a direction from the right to the left as viewed in Fig. 1 and hence in a direction opposed to that in which the thrust of the grinding wheel is exerted on the work. A suitable and preferred form of mechanism for this purpose may include a mounting 43 (see Fig. 4) supported from the slide 29 (Figs. 3 and 5) by a shaft 44 mounted for rotation in bearings 45 thereon. The shaft 44 is provided with eccentric portions 46 (Fig. 6) integral with or otherwise appropriately secured thereto, which are adapted to engage and rotate within bearings 47 (Fig. 4) in the mounting 43. A work moving member 48 (Figs. 1, 2 and 5) is adjustably secured upon the projecting arms 49 (Fig. 4)

on the mounting 43 by means of bolts 50 passing through the holes 51 in each arm. The mounting 43 is provided with an L shaped arm 52 extending rearwardly therefrom and projecting through a slot (see Fig. 5) in the bracket 27. The arm 52 has a bearing plate 53 adapted to slidably engage a bearing plate 54 on the bracket 27. The extent of the movement of the member 48 is limited by an adjustable stop screw 55 threaded into a lug 56 (Fig. 4) on the arm 52, the stop screw being arranged to engage the bracket 27. The mounting 43 is provided with a forwardly projecting guard 57 (Fig. 5) and an upwardly projecting guard 58, the latter being adapted for movement beneath a cover 59 extending downwardly and outwardly from the slide 29. The bearing plate 53 is held in contact with the bearing plate 54 by means of a plunger 60 pressed upwardly by means of a spring 61 surrounding a reduced portion of the plunger in a hole 62 in a lug 63 extending from the bracket 27. A bearing plug 64, through which the reduced portion of the plunger 60 passes, engages a threaded portion of the hole 62 so as to press against the spring 61 and thus permit of adjusting the compression on the spring.

When the work moving member 48 is withdrawn (in a direction to the right as viewed in Fig. 1), the finished work may be discharged. A preferred form of device for this purpose may include a reciprocating plunger comprising a hollow casing 65 (Fig. 2) adjustably mounted upon the water pan 33 by means of bolts 66 passing through a slot 67 in a downwardly depending bracket 68 integral with the casing 65. A hollow piston 69 is slidably mounted within the casing 65 and normally is held in the position shown in Fig. 2 by a spring 70 secured at one end to a pin 71 in the piston 69 and at the other end to a pin 72 in the casing 65. A pusher rod 73 is secured at the forward end of the piston 69 by a clamp 74 and bolt 75. The other end of the piston 69 is provided with an ear 76 which projects through a slot in the hollow casing 65 and is connected, in the device illustrated, to one end of a rope 77 passing around a pulley 78 mounted upon an arm 79 projecting from and integral with the casing 65. The rope 77 is connected at its other end with a manually operated device which may control the operation of the plunger as will be more clearly described hereinafter.

The mounting 43 for the member 48 and the reciprocating plunger may be actuated by the same or different devices, which may be controlled manually or by power through suitable mechanisms, but in the machine illustrated both are actuated by a single manually controlled device. For this purpose I provide a bifurcated lever 85 (Fig. 2) which is adapted to slide over and is pivotally mounted upon a plate 86, integral with or

otherwise appropriately secured to the bracket 27, to turn about a stud 87 fixed to the lever 85 and passing through the plate 86. An arm 88 is pivotally mounted to turn about a bolt 89 which is held in the plate 86 by a nut 90. The other end of the arm 88 is secured to one end of the rope 77. A link 91 is pivotally mounted at one end to the arm 88 and is provided near its other end with a slot 92 adapted to engage an upwardly projecting pin 93 in the lever 85. A rod 94 is pivotally secured at one end upon a stud 95 secured in a downwardly and forwardly extending crank arm 96 (Figs. 1 and 2). The other end of the rod 94 is pivotally mounted upon a stud 97 secured in a bifurcated end of a bolt 98 which is pivotally mounted on the lever 85 and is secured thereon by means of a nut 99. The crank arm 96 is rigidly secured to the shaft 44 by means of a key 101 (Fig. 6) engaging a slot 102 (Fig. 1) in the crank arm.

A bracket 103 (Fig. 1) is adjustably secured to the bearing casing 21 by means of bolts 104 passing through a slot 105 in an arm 106 extending downwardly from and integral with the bracket 103. A blade or work holding member 107 is adjustably mounted in the bracket 103 by means of bolts 108 passing through elongated slots 109 in the member 107. The bracket 103 is of hollow construction and is connected with a pipe 110 so that the grinding fluid or coolant may run out over the member 107 and directly upon the work *w* held between the regulating wheel 20, grinding wheel 12, member 48 and the member 107.

In operation, the grinding wheel 12 is rotated at a suitable grinding speed (in the direction indicated by the arrow in Fig. 1) from any appropriate source of power by means of the belt 13, and the regulating wheel 20 is rotated slowly (in the direction indicated by the arrow in Fig. 1) by means of the motor 23 and parts associated therewith. The regulating wheel 20 and the member 107 are moved vertically to an appropriate position for the particular size of work to be ground, by turning a hand wheel secured upon the shaft 38. The blade or member 107 is then moved horizontally to a suitable position as determined by the size of the finished work and the bolts 108 are tightened. The positioning member 48 may be adjusted vertically between the regulating wheel 20 and the grinding wheel 12 by turning the pinion 31 engaging the rack 32 to raise or lower the slide 29 upon which the holder 43 is mounted. The member 48 may be adjusted horizontally relative to mounting 43 by means of the bolts 50. The stop screw 55 is then adjusted so as to limit as desired the distance which the positioning member 48 may travel toward a line connecting the centers of the grinding wheel and regulating

wheel, that is, toward the left, as viewed in Figs. 1 and 5.

With the movable work holding or work positioning member 48 in its withdrawn position, that is, in a position to the right of that shown in Fig. 1, a work piece *w*, which may be assumed to be for example a work piece having a shoulder or enlargement thereon such as a bolt, is inserted manually or otherwise between the grinding wheel 12, regulating wheel 20, member 107 and the member 48, the enlarged or headed portion thereof overhanging the side face of the wheels and the end edges of the members 107 and 48. At this point it might further be noted that with the member 48 withdrawn toward the right, the inserted work piece rests upon the upper surface of the regulating wheel 20 and against the member 48, being out of contact with the grinding wheel 20 due to the fact that the adjacent operative surfaces of the two wheels are progressively more distant from each other throughout a substantial range extending substantially from the work engaging face of the member 107 toward the right as viewed in Fig. 1. The movable work holding member 48 during this period acts to prevent the work piece *w* from rolling off of the regulating wheel, the parts being so arranged, as will be clear from both Figs. 1 and 5, that the work piece *w* is positioned to the right of a vertical plane passing through the axis of the regulating wheel 20. Also during this period the slowly moving surface of the regulating wheel 20 keeps the work piece *w* rotating so that during the subsequent operations to be more clearly described hereinafter the ultimate contact of the work piece with the grinding wheel finds the work piece in an already rotating condition.

By thereupon moving the lever 85 to the left and into substantially the position shown in Fig. 1 or in a clockwise direction as viewed in Fig. 2, the shaft 44 is rotated to move the eccentric portions 46 thereon within their bearings 47 and move the mounting 43 together with the positioning member 48 forward (to the left as viewed in Figs. 1 and 5) towards the grinding throat. In this manner the positioning member 48 moved with the work *w* to move the latter laterally into contact with the grinding wheel and then feed or continue to move the work forward into the narrower portions of grinding throat and thus cause it to be progressively reduced in size. This member 48 maintains the work in operative contact with the wheels until it has been brought to the desired predetermined size as limited by the setting of the stop screw 55. Also the relatively fixed blade or work holding member 107 may be suitably set or adjusted to such a position that the work piece *w* will come in contact with it as soon as the work piece has been reduced to

the desired size, thus further preventing further movement of the work piece toward still narrower portions of the grinding throat. Care should be taken to make the adjustments such that when the work has been ground to finished size its center will not have passed a line connecting the centers of the wheels. It will therefore be noted that the grinding operation is preferably performed wholly in the rear of the center line, connecting the wheels where the latter are of the peripheral type and where one wheel is arranged above the other, thereby insuring a movement of the work piece in a direction transversely of its axis and between progressively narrower portions of the grinding throat formed by the two wheels. It is also to be noted that during these actions the regulating wheel 20 continues to control the rotation of the work piece *w* while the grinding wheel 12 performs a grinding operation thereon.

When the grinding has been finished, the lever 85 is moved toward the right as viewed in Fig. 1 (or in counterclockwise direction as viewed in Fig. 2) as quickly as is desired until the pin 93 is brought into engagement with the rear end of the slot 92 (Fig. 2). This movement of the lever 85 acts through the linkages 94-96 to rotate the eccentric shaft 44 in reverse direction and thus to commence the movement of the positioning member 48 in a direction toward the right as viewed in Figs. 1 and 5, thus permitting the work piece *w*, while still being rotated by the regulating wheel 20, to roll toward the right and into a wider portion of the grinding throat. As the movement of the lever 85 is continued toward the right, the arm 88 is turned about its pivot bolt 89 to pull upon the rope 77 and thereby move the piston 69 against the action of the spring 70 to force the pusher rod 73 axially between the wheels to discharge the ground work *w*. The lever 85 is then moved towards the left (as viewed in Fig. 1) until the pin 93 engages the forward end of the slot 92 thereby permitting the spring 70 to return the pusher rod 73 to the position shown in Fig. 2. With the lever 85 in this position the positioning member 48 stands in its rearward position a sufficient distance from the grinding throat to permit replacement of the work. A new work piece is then inserted between the wheels and in contact with the positioning member 48, and the movement of the lever 85 is continued toward the left at a rate governed by the skill and experience of the operator in the particular type of grinding operation being performed until the new work piece is brought to the desired predetermined size.

In Fig. 7 of the drawings, I have indicated in a diagrammatic manner the application of the invention to a type of centerless grinding machine in which the centers of the grinding wheel and the work regulating wheel are posi-

tioned in substantially the same horizontal plane. As illustrated, the grinding wheel 120 is mounted to be rotated rapidly in the direction indicated by the arrow by suitable mechanism, and the work regulating wheel 121 is similarly mounted for rotation slowly in the direction indicated by the arrow. A work piece is positioned between the wheels and is adapted to rest upon a movable positioning member 122 which is adjustably secured in a holder or mounting 123 by means of bolts 124 passing through elongated slots 125 in the positioning member. The holder 123 is mounted to turn about the eccentric portion 126 of a shaft 127 which is rotatably mounted upon a rigid portion of the machine, such for example as upon a plate or frame 128. A crank arm 129 is secured upon the shaft 127 by means of a key 130 therein adapted to engage a slot 131 in the crank arm. Movement of the positioning member 122 upward may be limited by a stop screw 132 adjustably mounted in a lug 133 in the frame 128 to engage the crank arm 129. It will be now apparent in view of the foregoing to those skilled in the art that the work may be fed into the grinding throat between the wheels so that it may be ground to a predetermined desired size by moving the crank arm 129 to the right, and the positioning member 122 may be withdrawn quickly to permit discharge of ground work by moving the crank arm to the left. Also, as will be seen in Fig. 7, I prefer in this form of apparatus to relate the parts so that upon movement of the work holding member 122 upwardly the work piece supported thereby will be moved toward the line connecting the centers of the two wheels and hence into contact with the less and less distant portions of the two wheels; this relation of the parts is clearly indicated in Fig. 7. Also, it will be seen that the work piece carried by the member 122 is moved in a direction opposed to the downward thrust of the grinding wheel thereon and that the extent of the grinding operation performed on the work while the latter is being rotated by the regulating wheel 121 may be predetermined by adjustment of the stop screw 132 which limits the movement of the crank arm 129.

It will therefore be seen that in accordance with certain features of the invention the work may be moved laterally into the narrowing grinding throat between the wheels in opposition to the thrust of the grinding wheel upon the work at a controllable rate, thereby assuring that the work will not be injured by becoming wedged in the throat between the wheels. It will further be noted that I effectively utilize the substantial thrust exerted by the grinding wheel on the work to tend to hold the work against the movable work holding member 48 and thus to assist in preventing the work piece from wedging in between the wheels. Furthermore, the invention provides

a machine adapted for economically and efficiently grinding successive work pieces having shoulders or enlargements thereon upon an efficient production basis to a predetermined size. It will be understood that I prefer to achieve the narrowing grinding throat for coaction with the work moving devices above described by utilizing peripherally opposed peripheral wheels but that I may achieve many of the features of this invention with other shapes of wheels. It will furthermore be seen that there has been provided in this invention an apparatus in which the several objects hereinbefore noted as well as many advantages are successfully achieved and that the apparatus is well adapted to meet the varying conditions of hard practical use.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

Having thus described my invention, what I claim as new and desire to secure by Letters Patent is:

1. A centerless grinding machine comprising a rapidly rotated grinding wheel, a slowly rotated work regulating wheel, a positioning member for maintaining work of round section in operative contact with the wheels, and means for moving said member in a direction substantially transversely of the axis of the work piece and in opposition to the thrust of the grinding wheel to cause the work to be ground to a predetermined size while being rotated by regulating wheel and thereafter withdraw it to permit removal and replacement of the finished work.

2. A centerless grinding machine comprising a rapidly rotated grinding wheel, a slowly rotated work regulating wheel, a work positioning member, means for adjusting said member laterally and vertically to accommodate different sizes of work, and a mechanism for moving said member to force the work into the grinding throat and cause it to be ground to a predetermined size and thereafter permit discharge of the work.

3. A centerless grinding machine comprising a rapidly rotated grinding wheel, a slowly rotated work regulating wheel, a work positioning member arranged to move work of round section into the grinding throat in a direction substantially transversely to the axis of the work and in opposition to the thrust of the grinding wheel so that the work may be ground to a desired predetermined size and thereafter to withdraw, and means for discharging the ground work axially when said member is withdrawn.

4. A centerless grinding machine comprising a rapidly rotated grinding wheel, a slowly rotated work regulating wheel, a movable

work positioning member, a mechanism for moving said member to force the work into the grinding throat in opposition to the thrust of the grinding wheel until ground to a predetermined size and thereafter withdraw, a reciprocable plunger for discharging the ground work when said member is withdrawn, and means for controlling the movement of said mechanism and said plunger and for causing said mechanism and said plunger to operate in proper sequence.

5. In grinding apparatus, in combination, a grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions, said wheels being opposed to one another and having their operative surfaces substantially approaching each other so as to form a grinding throat of varying width, and a movable member for holding work in operative relation to said two wheels, and means for moving said work-holding member in a direction substantially transversely of the axis of the work piece held thereby and with the work piece interposed between it and the narrower portion of said grinding throat so as to carry the work toward the narrower portion of said grinding throat, thereby to effect progressive reduction in diameter of the work, and means for limiting the movement of said work-holding member.

6. In grinding apparatus, in combination, a grinding wheel rotatable at a grinding speed, a slowly rotated work-regulating wheel, a member for holding work in operative relation to said two wheels, means for moving said member, with a piece of work to be ground in a direction opposed to that in which the thrust of the grinding wheel is exerted, thereby to cause the work to be ground to a predetermined size, and for thereafter withdrawing said member to permit removal of the ground work, a plunger movable in a direction to eject the work piece from the grinding throat formed by said two wheels and mechanism for operating said plunger only after the withdrawal movement of said work-holding member has commenced.

7. In grinding apparatus, in combination, a rapidly rotated grinding wheel, a slowly rotated work-regulating wheel, a movable member for holding work of round section between said wheels, and means for moving said member with a work piece thereon in a direction substantially transversely of the axis of the work, thereby to carry said work piece into the grinding throat formed by said two wheels, and in a direction to move and hold the work piece against the thrust of the

grinding wheel while being rotated by said regulating wheel.

8. In grinding apparatus, in combination, a grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling 10 in opposite directions and having their operative surfaces substantially approaching so as to form a grinding throat of varying width, means for moving a work piece substantially transversely of its axis into said 15 grinding throat, means for moving a work piece out of said grinding throat, a lever, means forming a direct connection between said lever and one of said means for actuating the latter by said lever, and means forming a 20 lost motion connection between said lever and the other of said means for actuating the latter by said lever.

Signed at Detroit, Michigan, this 27th day
